UNITED STATES PATENT OFFICE.

WILLIAM F. CONVERSE, OF HARRISON, OHIO.

INDIA-RUBBER SPRING.

Specification of Letters Patent No. 12,738, dated April 17, 1855.

To all whom it may concern:

Be it known that I, Wm. F. CONVERSE, of Harrison, Hamilton county, Ohio, have invented new and useful Improvements in 5 India-Rubber Springs; and I do hereby declare the following to be a full, clear, and exact description thereof, reference being had to the annexed drawings, making part of this specification.

10 My improvements have for their objects, 1, so incasing a cylindrical or spheroidal block of india rubber, as that an equal or nearly equal resilient force is exerted from every part of its perimeter, and in directions radiating from a common center, at or near the axis of the block, the surface of the block being in every condition of its action equally and completely incased. Such arrangement of the inclosing device is 15 found to result in a more complete, effective and enduring resilient action than where a portion is allowed to expand while another portion contracts. 2, facility for any desired extension of the range of action. 20 3, regulation of the resilient force.

In the annexed drawings Figure 1 is a perspective view. Fig. 2 is a transverse section and Fig. 3 an axial section of one form of my improvement.

30 (a) is a block of india rubber of cylindrical form and of about equal length and diameter and notched (b) along one side, to admit the hook of the toggle hereafter described. This block is traversed along its axis by a 35 bolt (c) furnished at one or both ends with nuts (p) which hold and press against the ends of the block, circular disks or heads (d), which confine the block in the direction of its axis, and by being screwed more or 40 less tight, afford a means of regulating the resilient force of the rubber. Washers (e), placed between the heads and the ends of the block, also afford a means of adjustment, and may be introduced of different thick- 45 nesses and number, according to the degree of tension desired for the rubber.

The heads, when once adjusted to their proper position remain stationary, their office being to oppose the expansion of the 50 rubber block in the longitudinal direction, when under the action of the compressing forces, which, instead of being applied longitudinally in the usual way, are made to

act exclusively in a radial direction, converging from all sides to a common line at 55 or near the axis of the block. This radial action toward a central line is produced by the following mechanism:

(f, g,) is a yielding case, sheath or strap, consisting of a series of hooked and bent 60 plates or cylindrical segments (f) united by links or bridles (g). The curve given both to segments and links, is such as to adapt them to the cylindrical surface of the block. The two extremities of this strap are linked 65 to a pair of levers (i i') near to their common fulcrum or point of contact, within the notch of the block. The ends, may be held together within the block by a hook (j) on one lever which retains within its concavity the V edge (h), of the other lever. The effect of compressing together the other or free extremities of the levers, is to draw 70 together the ends of the strap, and thus to contract it around the block. 75

The convex surface or head of the hook, is sufficiently expanded to hold back and press toward the center of the rubber, the portion not confined by the strap. By these means all parts of the rubber are pressed 80 toward a central line, at or near and parallel with the axis of the cylinder, the resistance of the rubber augmenting in every direction, as the levers approach the rubber not being permitted to expand in one direction, while 85 contracting in another, and the block being in every condition of action and inaction pressed equally on all parts of its surface, and constantly preserving the cylindrical form, under all circumstances. Thus is 90 remedied a defect inherent in all india rubber springs, wherether subjected to an extensional or compressible force where the entire surface is not supported the defect 95 consisting in the undue disturbance (contraction or expansion) of the middle portions.

It will be seen that in the most extended position of the levers, they act with a less powerful leverage than in the compressed 100 position, but have of course a far less resilient force to overcome than when brought closer together. In order however to enable the initiatory action to be made as prompt as may be desired, the concave surfaces of the segments are grooved (n) at 105

right angles with the axis, so that the opposing resilience of the block does not react against the entire surface of the strap until all the grooves are filled. The amount of action of these grooves will depend on their form, depth, and number which may be varied to suit the object of the constructor. Another beneficial action of these grooves is that their ridges serve as so many heads, to act in concert with the external ones in equalizing the longitudinal strain of the block when under a heavy pressure. The form of the block may in some cases, be slightly varied from the cylindrical one, as for instance it may be prolately spheroidal or even prismatical. The range of the levers may be one half of their length or less according to circumstances. Only a small portion is here shown of the length of lever intended in actual use.

The levers themselves may be forged or cast of the whole length required for use, or if made shorter, as in the illustration may be bolted, welded, or riveted to suitable bars or plates. These bars or plates, not being required to spring should have their greatest width in the direction of the motion, so as to combine lightness with strength; they may be made of steel, wrought iron or malleable cast iron, and may be formed to suit the circumstances of their application. If the metallic parts are of malleable or wrought iron, the working surfaces may be case hardened. This plan of spring is applicable to carriages, mortising machines, saddle trees and other objects to which springs are applied.

For carriages, one short bar may be attached to the holster, and a longer one be made to rest upon the axle bed or head block as the case may be—or in any other mode that the nature of the vehicle or judgment of the manufacturer may indicate.

A spring thus formed will be found to be more cheaply constructed, more enduring and reliable, not subject to become impaired in its effective force or brittle with use, and by the application of the described levers and toggle or fulcrum in this connection, the spring can be made to act with a range and efficiency equal to the best steel spring; and should it be desired at any time to apply a different size or quality of rubber, a new block can be inserted at the cost of a few cents. In no other plan of india rubber spring known to me, is the action effected by a pressure from all parts of the perimeter toward an axial line by contracting the case radially upon the rubber. Where desired, the range of the levers may be limited by a stirrup (*k*) as represented or by a headed pin or by flanges projecting from the heads.

I prefer a jointed case such as described, to wires or to a pliable steel or iron band, because there is no strain of the cohesive

power of the metal by bending. Neither are cords of gut or hemp so desirable for permanent purposes as metal, because they are liable to stretch and to become brittle with age.

The rubber used may be of the vulcanized kind employed for the springs of railroad cars.

Fig. 4 represents a modification of my invention in which the jointed strap is replaced by strong cords, gut, or wires (*l*).

Figs. 5 and 6 represent by transverse section and side view an arrangement of interlocking fingers (*q*) bent to a cylindrical form to fit the block, and attached eccentrically to the confining pin (*c*)—the flanges or levers (*i i'*) in the illustration being so disposed and attached as to adapt the device to closing doors.

In Fig. 7 the office of the strap is served by a steel band (*m*).

Fig. 8 exhibits the application of a compressing cord in place of the jointed strap, and may be used for a door spring or like purpose where the action is effected by closing the levers together.

I regard the compound lever and the adjustable heads as represented, as valuable and novel but not absolutely essential adjuncts to my original device. In the majority of the many purposes to which the invention may be applied, one end of the strap will—instead of being united to a lever—be attached directly either to the bearing or to the moving object itself. A probably very prevalent construction, for a great variety of light purposes, (such as door springs, furniture cushions, &c.) will be, to forge or cast the heads solid to a single lever; a simple flange—for direct attachment to the object—being substituted for the other lever; in which case the central bolt and the adjusting nuts may be dispensed with.

For mortising machines, embossing presses, carriage springs, and other purposes requiring great resilient power, some convenient means of adjustment will be desirable, and may be effected either in the manner illustrated, or by metallic disks, or by keys applied either to the heads or to the strap connections.

The elastic block may be composed of caoutchouc—vulcanized or otherwise—or of a suitable mixture of caoutchouc and gutta-percha; and from the yielding nature of such materials, a variety of shapes will serve with nearly equal efficiency; providing the capacity of the block is such as to exactly fill the cavity of the strap when merely contracted to its normal or inactive condition.

I am aware that springs of india rubber and other similar materials have been completely confined in cylindrical and other unyielding cases. Such an arrangement therefore I do not claim; but

What I do claim as my invention and desire to secure by Letters Patent is—

The method of confining a cylindrical or prismatic block of india rubber at all points 5 of its surface, by means of a jointed or otherwise flexible cylindrical strap, connected to double levers or their equivalents, for applying the compressing strain, convergently or radially upon the inclosed rubber; I likewise 10 claim in this connection adjustable end plates for securing the rubber from lateral

expansion, and for graduating the elastic force of the spring if desired by means of screw nuts or equivalent devices substantially as herein described. 15

In testimony whereof, I hereunto set my hand before two subscribing witnesses.
